US0D1047996S

(12) **United States Design Patent** (10) Patent No.: **US D1,047,996 S**
(45) Date of Patent: ** Oct. 22, 2024

(54) **PORTABLE COMPUTER**

(71) Applicant: **Dell Products L.P.**, Round Rock, TX (US)
(72) Inventors: **Jeff A. Reed**, The Hills, TX (US); **Nicholas G. DiLoreto**, Georgetown, TX (US); **An-Chung Hsieh**, New Taipei (TW); **Yongook Guack**, Leander, TX (US); **Duck Soo Choi**, Georgetown, TX (US)

(73) Assignee: **Dell Products L.P.**, Round Rock, TX (US)

(**) Term: **15 Years**

(21) Appl. No.: **29/828,655**

(22) Filed: **Feb. 28, 2022**

(51) LOC (14) Cl. **14-02**

(52) U.S. Cl.

USPC **D14/315**

(57) **CLAIM**

The ornamental design for a portable computer as shown and described.

DESCRIPTION

FIG. 1 is a front perspective view of the portable computer comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 is a front perspective view of the portable computer in an open position.

Broken lines shown in the drawings illustrate portions of the portable computer that form no part of the claimed design.

1 Claim, 7 Drawing Sheets
